C. Washburn,

Latch.

Patented April 18, 1832.

Calvin Washburn of Bridgewater, Massachusetts
Letter Patent.)

The schedule referred to in these Letters Patent and making part of the same, containing a description in the words of the said Calvin Washburn himself, of his improvement in the construction of Door fasteners.

To all to whom these presents shall come. Be it known that I, Calvin Washburn of Bridgewater in the County of Plymouth and State of Massachusetts, have invented a new and useful improvement in the construction of Door Fasteners and that the following is a full and exact description of the construction and operation of said improvement as invented by me. The improvement consists in a bolt or catch of brass, iron or metal, which is fixed or hung upon a straight spiral, or other shaped spring, which spring throws or forces out the bolt or catch into a cavity or hole prepared to receive the same (thus holding or retaining the door firmly in its place when shut) and a short lever to disengage the same bolt or catch from the hole or cavity so as to open the door one end of this said lever is fixed or attached to a short gadgeon passing through or across and working the same, with handle at either or both ends - the other end of said lever is allowed to work freely up and down in the aforesaid hole or cavity. When the handle or handles are turned by applying the hand, this last aforesaid end of the lever is carried upward thereby forcing the bolt or catch back-ward into a cavity prepared to receive the same - the door is then disengaged and free to open, as soon as it is over the lower end of the lever being freed from pressure drops to the bottom of said hole or cavity which receives the bolt or catch, & the door is free to be shut or closed - A plate of iron or other

Oct. 18, 1832

metal with a hole in it corresponding to the shape of the bolt or catch is fastened around the hole or cavity which receives the bolt or catch when the door is shut, to protect the material of which the door is made from wearing away at that part which passes over or out against said bolt or catch, and another similar plate around the aperture through which the spring with the bolt or catch attached works.

The inventor makes use of hickory, or handles of brash
gloves or other material and of the common thumb piece
with the Norfolk handles in common use, in the inventor
claiming as his improvement the Spring Bolt or catch with the
mortised - lever acting upon the same as hereinbefore described
other material may be used and differently combined, than
is described in the preceding Specification, and he thinks it
proper to state that any approximation to the general method
of constructing, as herein before described which shall be embraced
the same be considered as coming within the real and just
extent of his invention

In testimony that the above is a true specification
of my said improvement I have hereunto set my hand and
seal this 26th day of March A.D. 1832.
